(57) **CLAIM**

The ornamental design for a tailgate cargo enclosure, as shown and described.

DESCRIPTION

The claimed tailgate cargo enclosure is used to extend the cargo bed of a vehicle and could be mounted on a truck.

FIG. 1 is a perspective view of a tailgate cargo enclosure illustrating our new design mounted on a rear portion of a vehicle.

FIG. 2 is a front perspective view of the tailgate cargo enclosure of FIG. 1.

FIG. 3 is a rear elevational view of the tailgate cargo enclosure of FIG. 1.

FIG. 4 is a front elevational view of the tailgate cargo enclosure of FIG. 1.

FIG. 5 is a top plan view of the tailgate cargo enclosure of FIG. 1.

FIG. 6 is a bottom plan view of the tailgate cargo enclosure of FIG. 1.

FIG. 7 is a left side view of the tailgate cargo enclosure of FIG. 1; and,

FIG. 8 is a right side view of the tailgate cargo enclosure of FIG. 1.

The broken line showing of environment is for illustrative purposes only and forms no part of the claimed design.

The tailgate cargo enclosure is shown on an enlarged scale in FIGS. 2-8.
